(57) **CLAIM**

The ornamental design for a skylight, as shown and described.

DESCRIPTION

FIG. 1 is a front perspective view of a skylight in accordance with our new design;

FIG. 2 is a rear perspective view thereof;

FIG. 3 is a front elevational view thereof;

FIG. 4 is a right side elevational view thereof, the left and right sides and the top and bottom of the skylight all being symmetrical to one another; and,

FIG. 5 is a rear elevational view thereof.

The broken line showing of portions of the design is included for the purpose of illustrating environment and forms no part of the claimed design.
